UNITED STATES PATENT OFFICE.

JOSHUA R. JONES, OF PHILADELPHIA, PENNSYLVANIA.

DESIGN FOR A BOOK-COVER.

SPECIFICATION forming part of Design No. 29,359, dated September 20, 1898.

Application filed August 17, 1898. Serial No. 688,811. Term of patent 3½ years.

To all whom it may concern:

Be it known that I, JOSHUA R. JONES, a citizen of the United States, residing at Philadelphia, in the county of Philadelphia and State of Pennsylvania, have invented and produced 5 a new and original Design for Book-Covers, of which the following is a specification, reference being had to the accompanying drawing, forming part hereof.

10 The leading feature of my design may be said to be the representation of a bell, more specifically the bell commonly known as "The Liberty Bell," associated with rococo ornaments or scrolls and stars and so arranged as 15 to constitute center and corner ornaments displayed upon a field or solid ground.

In the drawing, *a* is the representation of the bell.

b are rococo ornaments.

20 *c* are stars, and *d* are flags and border ornaments.

Incidentally it may be stated that I contemplate a reflecting effect upon the surface of the larger bell, and I range the described ornaments in relation to each other and to 25 the field or ground in such manner that center and corner ornaments are produced, as shown in the drawing.

Having described my invention, what I claim as new, and desire to secure by Letters 30 Patent, is—

The design for a book-cover substantially as shown and described.

In testimony whereof I have hereunto signed my name.

JOSHUA R. JONES.

In presence of—

D. LOPHAR HOWELL,
NEWTON H. JONES.
